UNITED STATES PATENT OFFICE.

GEORGE W. MENEFEE, OF BERKELEY, CALIFORNIA.

WINDLASS.

SPECIFICATION forming part of Letters Patent No. 757,668, dated April 19, 1904.

Application filed May 27, 1903. Serial No. 158,984. (No model.)

To all whom it may concern:

Be it known that I, GEORGE W. MENEFEE, a citizen of the United States, residing at Berkeley, in the county of Alameda and State 5 of California, have invented certain new and useful Improvements in Windlasses, of which the following is a specification.

My invention relates to improvements in windlasses, and especially to that class of 10 windlasses which are operated by means of friction devices which connect the winding-drum with a constantly-revolving wheel or disk driven from any suitable source of power.

The objects of my invention are, first, to 15 prevent, reduce, or control the backward movement of the winding-drum by a brake which is kept on while the drum is winding up its rope, which brake permits the drum to wind up the rope, but automatically prevents 20 its unwinding; secondly, to provide an improved device for thrusting the drum endwise against the driving-wheel; thirdly, to provide an improved friction-ring for imparting motion from the driving-wheel to the 25 drum; fourthly, to provide an adjustable and automatic device to cause the drum and winding-wheel to engage with just sufficient friction to wind up the slack rope slowly or to hold it from unwinding freely and at too high 30 a speed under its own weight.

Some of the purposes to which my improved windlass may be put are to run elevators, to operate hauling-ropes on ships and elsewhere, and to wind up or hold fast a rope 35 or chain for operating cableway conveyers. Other uses and purposes to which my invention may be used will readily suggest themselves.

My invention therefore resides in the novel 40 construction, combination, and arrangement of parts for the above ends hereinafter fully specified, and particularly pointed out in the claims.

In the accompanying drawings, Figure 1 is 45 a vertical section of the windlass, the upper part being taken through the end of the windlass adjacent to the brake-wheel and the lower part being taken slightly nearer to the other end to show the brake-lever in full. Fig. 2 is a horizontal section of the windlass 50

through the main shaft. Fig. 3 is a side elevation of the driving or friction wheel. Fig. 4 is a detail side view of the operating-lever. Fig. 5 is a view of the same at right angles to Fig. 4. Figs. 6 and 7 are detail face views of 55 the ratchet-toothed collars.

Referring to the drawings, 1 represents the frame of the windlass, comprising suitable pieces 2, secured together by ties 3. In said frame is revolubly mounted a shaft 4, which 60 carries, preferably keyed thereon, as shown at 50, a driving-wheel 5, having gear-teeth 6 on its periphery engaged by a pinion 7 on a shaft 8, operated from any suitable source of power. In the present instance I have shown 65 a sprocket-wheel 9 on said shaft 8 for operating the same from an engine at a distant point. Upon the face of said driving-wheel 5 are mounted the friction-ring sections 10, of wood, paper, or other suitable material, which 70 when placed in position form a continuous ring and are secured in position by means of a flat band 11, of metal, bolts 12 being used to secure said band, friction-ring sections, and driving-wheel together. The friction- 75 ring thus formed is wedge-shaped in cross-section, as clearly shown in Fig. 2, to engage the sides of an annular trough 13, formed in the end of the winding-drum 14. Said drum is movable lengthwise upon the shaft 4, so 80 that the sides of the trough are brought into engagement with the sloping sides of the friction-ring.

15 is a brake-wheel loosely mounted upon a shaft and slideable thereon, having a peripheral 85 groove 16 to receive a brake-band 17. In said groove are fitted the wooden brake-blocks 18, upon which the brake-band rests. On one side of the brake-wheel is secured a removable ring 19, which closes on one side the 90 groove in the periphery of said wheel and holds the band 17 in place, and the inner edge of said ring 19 extends inward within the periphery of the end of the winding-drum 14, thus preventing the brake-wheel from separating from the drum. The ends of said 95 brake-band are secured, as shown at 20, to a disk 21, mounted upon a shaft 22, having bearings in the frame of the windlass, and to said disk is secured a lever 23 for tightening 100

said brake-band upon the brake-wheel. The points of attachment of the brake-band to the disk are so located that a downward movement of the lever draws the upper one of said 5 points of attachment in a tangential direction relative to the brake-wheel and the lower one in a radial direction with reference thereto, so that such downward movement has the effect of tightening the band upon the brake-wheel. The lever 23 is provided with a series 10 of holes 24, by means of any one of which may be secured a clevis 25, supporting a suitable weight 26. The effect of this weight is to normally maintain said brake-band tight 15 around the brake-wheel.

To the end of the lever 23 is attached a rope 27, which passes over a pulley 28, and thus provides means whereby the operator can lift 20 the lever, permitting the brake-band to slacken and taking the brake off the brake-wheel and drum, thus allowing the drum and brake-wheel to turn backward.

The end of the drum has an annular series 25 of internal notches 33, which are engaged by dogs 34, pivotally mounted upon the inner face of the brake-wheel by means of shouldered bolts 35, said dogs being normally thrown into engagement with the notches by means of springs 36. Said notches and dogs are so 30 located with reference to each other that only one of said dogs is in engagement with a notch at the same time, the ends of the other dogs being at regularly-increasing distances from the notches. The effect of this is to provide 35 that the winding-drum shall revolve backward not more than one-quarter the depth of a notch before it is arrested by the engagement of a notch with one of the dogs.

The arrangement of the springs and dogs is 40 also so contrived that said dogs and springs can be turned over to point in the opposite direction, but at substantially the same angles with the notches, so that the operation of the brake-wheel may, if desired, be reversed in 45 direction.

For the purpose of throwing on the power to operate the windlass it is necessary that the drum and brake-wheel shall be shifted longitudinally, and for this purpose I provide the 50 following contrivance: Secured to the frame of the windlass by means of a bolt 37 is a plate 38, having secured thereto a collar 39 around the shaft 4, having four crown ratchet-teeth 40. A collar 41, similar to the collar 55. 39, but movable upon the shaft 4, is secured to a plate 42, similar to the plate 38, and said plate 42 is bolted to a handle-bar 43. The opposing faces of said ratchet-teeth thus form wedge-surfaces, so that when one of said collars is removed relatively to the other they are wedged or spread apart, and these collars being interposed between the hub of the brake-wheel and the frame of the winding-drum, thus spreading apart will have the effect 65 of causing the drum and the brake-wheel

to move lengthwise toward the friction or driving wheel, thus bringing the annular trough in the end of the drum into engagement with the sides of the friction-ring and causing the windlass to rotate with said friction or driving wheel. I provide an automatic means for maintaining said friction-wheel in engagement with said winding-drum, said means comprising a weight 44 of any desired magnitude mounted adjustably longitudinally 70 on the handle. By placing said weight at the proper position upon the handle it may be so arranged that the winding-drum will be engaged with the friction-ring with sufficient force to raise a given weight. This is of special value for raising unloaded ropes and winding the same on the winding-drum, for which purpose the weight 44 will be moved close to the inner end of the handle; but it may also be used as an automatic device for 75 raising heavy weights, in which case the weight will be moved to the outer end of the handle.

To prevent the endwise movement of the shaft, the ends of the shaft 4 are grooved, as 80 shown at 45, and a suitable set-collar 46 is provided at each end thereof, especially at the end farthest from the friction-ring.

Supposing that it is desired to wind up weight upon the winding-drum, the first operation is to throw over the handle-bar 43, the extended end of which rests against a stop 47 when the windlass is not in use. The effect of throwing the handle-bar over is to move the winding-drum and the brake-wheel 95 endwise against the friction-wheel, and thus to communicate motion to said winding-drum from said friction or driving wheel. It will not be necessary to hold the handle-bar in the position to which it has been thrown, as 100 the weight will be sufficient to maintain it in such position, said weight being so adjusted for the purpose as to distance from the fulcrum.

To arrest the winding movement, the handle is returned to its former position, when the winding-drum no longer revolves. The backward movement of the winding-drum is then arrested by means of the brake-wheel through the intermediate dogs and notches 115 and by the friction of the brake-band on said brake-wheel, said brake-band being held tight on said wheel by means of the weighted lever 23. If, however, it is desired to allow the winding-drum to pay off rope, this can be 120 done by raising the lever by means of the rope 27, which slacks the pressure of the band upon the brake-wheel. Releasing said rope instantly puts on the brake again and stops the winding-drum.

I claim—

1. The combination of the friction-wheel, the winding-drum arranged to be brought into engagement with said friction-wheel by an endwise movement, the brake-wheel hav- 130

- ing a connection with the winding-drum permitting rotary movement of the latter in one direction while arresting it in the other, the brake-band around said brake-wheel, a lever 5 for operating said brake-band, a weight normally holding said lever in its operative position, and means for raising the lever against said weight to release the brake-band, substantially as described.
- 10 2. The combination of the friction or driving wheel, the winding-drum arranged to be brought into engagement with said driving-wheel by an endwise movement, and the brake-wheel, mounted concentrically with the winding-drum, said brake-wheel and drum having, the one a series of notches, and the other a dog engaging the notches in succession, permitting the movement of the winding-drum in one direction while preventing its movement in the opposite direction, a brake-band around the brake-wheel, means for normally holding said brake-band tight therearound, and means for loosening the brake-band when desired, substantially as described.
- 15 3. The combination of the friction or driving wheel, the winding-drum adapted to be engaged by said driving-wheel, the brake-wheel at the end of the winding-drum opposite to the driving-wheel, and means for oper- 20 atively connecting said winding-drum and brake-wheel comprising a circular series of notches on one of said elements and a series of spring-actuated dogs on the other element, said dogs being unsymmetrically arranged with 25 reference to said notches so that only one of them can be in engagement with a notch at the same time, substantially as described.
4. The combination of the friction-wheel, the winding-drum, the brake-wheel having an 30 operative connection with the winding-drum

to restrain its rearward movement and the ring secured upon the side of the brake-wheel and overhanging the periphery of the end of the winding-drum, substantially as described.

5. The combination of the winding-drum, 45 the brake-wheel having a connection with the winding-drum permitting rotary movement of the latter in one direction while arresting it in the other, the brake-band around said brake-wheel, a lever for operating said brake-band, a weight normally holding said lever in its operative position, and means for raising the lever against said weight to release the brake-band, substantially as described.

6. The combination of the winding-drum, 55 the brake-wheel at the end of the winding-drum, and means for operatively connecting said winding-drum and brake-wheel comprising a circular series of notches on one of said elements and a series of spring-actuated dogs 60 on the other element, said dogs being unsymmetrically arranged with reference to said notches so that only one of them can be in engagement with a notch at the same time, substantially as described.

7. The combination of the winding-drum, the brake-wheel having an operative connection with the winding-drum to restrain its rearward movement, and the ring secured upon the side of the brake-wheel and over- 70 hanging the periphery of the end of the winding-drum, substantially as described.

In witness whereof I have hereunto set my hand in the presence of two subscribing witnesses.
